POPPED CORN DISPENSING APPARATUS

Samuel Pinanski, Brookline, Mass., assignor to
American Theatre Supply Corporation, Boston,
Mass., a corporation of Massachusetts

Application May 1, 1951, Serial No. 223,979

4 Claims. (Cl. 34—199)

1

This invention relates to dispensing apparatus and more particularly to dispensing apparatus of the type disclosed in Patent No. 2,423,342 for dispensing popped corn which, to be palatable, must be delivered to purchasers in a hot and crisp condition.

The principal object of the present invention is to provide an improved dispensing apparatus of the character described for maintaining the initial crispness of the total supply of comestible material within the apparatus and particularly at the immediate dispensing area where it is freely accessible for removal in successive small amounts when the apparatus is in use. A further object is to provide an improved dispensing apparatus having the above characteristics which will preserve the initial crispness of the supply to an extent heretofore unattained in the art while at the same time producing this improved result more economically and efficiently. Further objects are to provide an improved dispensing apparatus having the above characteristics but of simple and inexpensive construction, of a portable character and pleasing appearance, which is of rugged and durable construction, sanitary and easily cleaned and from which the contents may easily be dispensed, and which automatically maintains the proper temperature conditions and air velocity for insuring the desired results. A further object is to provide an improved dispensing apparatus having the above characteristics which, when not in use, may be tightly closed to prevent the entry of dust or moisture.

Other and further objects and advantages of the invention will be apparent from the following more detailed description and by reference to the accompanying drawings in which

Fig. 1 is a front elevation of apparatus embodying the invention;

Fig. 2 is a plan view of the apparatus shown in Fig. 1 with certain parts broken away and shown in section and with the dispensing drawer in open position;

Fig. 3 is a vertical section to a larger scale, on the line 3—3 of Fig. 2, indicating in broken lines the dispensing drawer in closed position;

Fig. 4 is a vertical section on the line 4—4 of Fig. 3 to a smaller scale; and

Fig. 5 is a fragmentary vertical section to a larger scale, on the line 5—5 of Fig. 2.

Referring to the drawings the numeral 1 designates in general a portable display and dispensing cabinet which can be placed upon any suitable support such as a table top, bench or

2

counter and which, in a preferred construction, consists to a major extent at least of sheet metal and glass. The cabinet has a base portion comprising the bottom member 2 (Figs. 3 and 4) of sheet metal, the end walls 3 and 4 (Figs. 1 and 4) which in a preferred construction are of substantially semi-cylindrical shape in plan and the rear wall 5 (Fig. 3) which is substantially straight.

10 The forward edges of the end walls 3 and 4 are spaced apart to provide for the reception between them of a dispensing drawer as herein-after described. The lower edges of the walls 3, 4 and 5 are secured to the bottom wall 2 in any desired manner, for example by using rolled joints commonly employed in sheet metal work, or they may be otherwise or additionally united, for example by solder or welding.

15 The upper portions of the walls 3 and 4 are stiffened and held rigidly in proper shape by means of angle bars 6 and 7 (Fig. 4) whose vertical flanges are bent to substantially the same semi-cylindrical curvature as the walls 3 and 4. The vertical flanges of the bars 6 and 7 are secured to the walls 3 and 4 by spot welding, for example.

20 The horizontal flanges 8 and 9 of the bars 6 and 7 are directed inwardly and form supports for the lower edges of the vertically elongate semi-cylindrical transparent panels 10 and 11 (Fig. 4) and a vertically elongate flat panel 15 (Fig. 3). The panels 10, 11 and 15 may be made of glass or other transparent material such as one of the synthetic resins, and they form the end walls and rear walls respectively of the upper or storage chamber of the cabinet.

25 The rear vertical edge of the panel 10 and adjacent vertical edge of the rear panel 15 are joined together by suitable means as a joining strip 13 (Fig. 2) having opposed channels which engage and receive the vertical ends of the panels 10 and 15 respectively. An elongate vertical member 14 has flanges 17 and 17a engaging the front faces of the panels 15 and 10 respectively on opposite sides of the strip 13, the base of the member 14 being spaced from the front face of the joining strip 13 so as to form between them a vertical flue 16 (Fig. 2). The flanges of the member 14 are held in engagement with the front faces of the panels by suitable means here shown as screws interconnecting the member 14 with the joining strip 13. The panel 11 is joined to the opposite vertical edge of the rear panel 15 in the same manner as above described for the panel 10.

The upper edges of the panels 10 and 11 are disposed within downwardly open channel members 18 and 19 (Fig. 4) suitably curved to conform to the panels 10 and 11, and these channel members 18 and 19 support top plates 20 and 21 (Fig. 4) respectively, of sheet material which form top closures for the semi-cylindrical spaces within the panels 10 and 11. These plates 20 and 21 are secured air-tight to the channel members 18 and 19, for example by soldering, brazing, or by appropriate rolled joints.

A rear top member 22 has a flange 23 which overlaps the upper edge of the back member 15 and which is secured to the latter by solder, welding or the like, the top member 22 extending from the inner edge of the plate 20 to the inner edge of the plate 21 and being united to the latter by welding or soldering, and extending forwardly a distance preferably substantially half the front-to-rear width of the cabinet. At its forward edge this plate 22 is secured to an angle bar 27 (Fig. 3). Hinges 24 pivotally connect a cover member 25 to the plate 22, so that the cover member may be swung upwardly and rearwardly. The rear edge of this cover member normally rests against the horizontal flange of the angle bar 27, the cover being provided with a knob 26 by means of which it may be raised.

The forward edges of the transparent panels 10 and 11 are housed in vertical channel members 28 and 29 which form the sides of an opening for the reception of a front door having a frame 30 which is hinged at 31 to the right-hand member 28. The door preferably has a latch 33 at its left-hand side engageable by a suitable retainer on the left-hand member 29. The upper portion of this door frame constitutes a support for the forward edge of the cover 25. Preferably the door has a transparent panel 34 of glass or other suitable material.

The bottom member 2 of the base of the cabinet supports a layer 35 (Fig. 3) of insulating material and the side walls and back of the base are preferably insulated.

Between the forward vertical edges of the end walls 3 and 4 of the base portion is a relatively low front wall 36 secured to the bottom wall 2 and insulated as walls 3, 4 and 5. Inwardly of said front wall are spaced pairs of U-shaped supports 37 and 38 (Figs. 3 and 4) having their lower legs fixed to the bottom wall 2. Parallel, elongate runners or tracks 39 and 40, Z-shaped in cross section, have the lower leg of the Z fast to the upper leg of the U-shaped supports respectively and the upper leg of the Z extends laterally outwardly from the U-shaped support and forms a support spaced from the bottom wall 2 at the same height as the upper edge of the front wall 36 for the bottom 41 of a dispensing drawer (Figs. 3 and 4).

The drawer has a front wall 42 which extends above the base preferably substantially to the lower edge of the front door and laterally beyond the vertical inner edges of the end walls 3 and 4 to overlap the same and downwardly below the upper edge of the front wall 36. The drawer also comprises side walls 44 and 45 (Figs. 2 and 3) and a relatively low rear wall 43. The lower edges of the side walls extend below the bottom 41 and thence inwardly to form flanges 44a and 45a (Fig. 4) which slidably engage the lower faces of the upper leg of the Z-shaped runners 39 and 40. The side walls and bottom of the drawer are at all times in sliding engagement with adjacent inner vertical edges of the end

walls 3 and 4 and the upper edge of the front wall 36 respectively.

An upwardly turned flange 46 (Fig. 3) connects the bottom 41 of the drawer and the front wall 42 and a handle 47 is secured to the outer face of the front wall to facilitate the sliding movement of the drawer outwardly to the dispensing position shown in full lines in Fig. 3 and inwardly to the closed position shown in dot and dash lines in Fig. 3.

To provide a stop for limiting the outward movement of the drawer, spaced brackets 48 and 49 (Fig. 4) are fixed to the rear face of the rear wall 43 of the drawer for slidably accommodating L-shaped fingers 50 and 51 which extend downwardly below the bottom of the drawer inwardly of the Z-shaped runners 39 and 40. Lugs 52 and 53 are secured intermediate the ends of the Z-shaped runners to the upper faces of the lower leg of the Z-shaped runners and project inwardly under the bottom of the drawer. Thus, as the drawer is pulled outwardly, the lower portions of the fingers 50 and 51 engage the lugs 52 and 53 to limit further outward movement thereof.

The drawer is also provided with a forwardly and downwardly inclined perforate false bottom 54 supported above the bottom 41 of the drawer preferably throughout the length of the drawer by suitable means here shown as pairs of transversely spaced front and rear legs 55 and 56 thereby, together with the side walls and bottom of the drawer, to form a forwardly tapered chamber 57 (Fig. 3). The rear edge of the false bottom is spaced substantially higher than the upper edge of the rear wall 43 thereby to form an inner open end to the chamber 57 to permit free passage of air into said chamber from the space behind the rear of the drawer. If desired, that portion of the bottom 41 of the drawer which remains within the cabinet when the dispensing drawer is in operative position may be provided with transverse perforations.

The angle bars 6 and 7 (Fig. 4) support perforated plates 58 and 59 (Figs. 1 and 4) which form the floors of the spaces within the end panels 10 and 11, and also support a perforated plate 60 forming the floor of the main portion of the storage chamber. The perforated portion of plate 60 terminates at a line 61 (Fig. 3) spaced from the plane of the front wall of the cabinet, the plate then extending down to form an apron 62 which is engaged by an upwardly turned flange 63 at the rear end of the false bottom 51 when the dispensing drawer is in open position.

The apron 62 and flange 63 constitute the effective rear wall for the dispensing chamber D of the dispensing drawer, said dispensing chamber being further defined by the false bottom 54, side walls 44 and 45 and front wall 42. The dispensing chamber D of the drawer always freely communicates with the storage chamber above the floor 60 by means of the aperture 64 at the forward edge of the plate 60. Through this aperture the material in the storage chamber flows by gravity into the dispensing chamber D of the drawer.

To the members 28 and 29, below the front door, there are secured a pair of hinged wings 66 which, when the drawer is pulled forwardly into operative position, may be swung into the position shown in Fig. 3 so as to form upward extensions of the side walls 44 and 45 of the drawer, thus providing an open-topped dispensing chamber having an effective depth at its forward portion of substantially the height of the

forward wall 42 of the drawer. One wing 66 and its hinge 67 are shown in Fig. 3. In order to guard the opening below the front door, when the wings are disposed as shown in Fig. 3, there is provided a flap 69 pivotally supported by the hinge 70 and closing the space between the lower portions of the parts 28 and 29.

The members 14 are formed with vertically spaced perforations 71 (Fig. 2) and the upper and lower ends of the flue 16 are open at 72 and 73 (Fig. 3) respectively.

In the semi-cylindrical space within the wall 3 and between the bottom 2 and perforated plate 58 is a triangular shaped air box 75 comprising side walls 3, 76 and 77, bottom wall 2 and a removable cover 78 which rests on the top edges of the side walls 76, 77 and the horizontal flange of an angle bar 79 fast to the side wall 3. Air from outside the cabinet is drawn into the box 75 by a suitable motor driven blower 80 mounted in said box, the air passing through an aperture 81 provided in the side wall 3 and through an outer screen 82, filter 83 and inner screen 84. The filter and inner screen are removably held within the aperture by suitable means here shown as a vertical Z-shaped strip 65 and an angle strip 85 fast to the inner faces of side walls 3 and 77 respectively. In replacing the filter the cover 78 of the box is removed and the filter is slid upwardly out of the upper open ends of the strips 65 and 85.

Rearwardly of the air box 75 is a heater casing 86 connected to the blower 80 through an aperture in the side wall 77 and which receives air at superatmospheric pressure from the blower. Electric current is supplied through conduit 87 (Fig. 2) connected to any suitable source of power, the conduit entering a distributing and fuse box 88 mounted on the heater casing 86 by suitable means as bolts and from which cables 89 and 90 lead to the blower motor 91 and to a heating coil 92 of any suitable type arranged within the casing 86.

An air conduit 93 extends rearwardly from the heater casing 86 and terminates with its delivery mouth 94 directed toward the space between the bottom wall 2 and perforate plate 60. At the delivery mouth of the air conduit a thermostat 95 is mounted on the air conduit and it has its temperature responsive element 96 extending directly into the conduit where it is exposed to the air flowing therethrough. A cable 97 connects the thermostat through the distributing box and cable 90 with the heating coil 92 whereby the thermostat controls the flow of current to said heating coil.

Preferably, in the upper portion of the cabinet (Fig. 3) there is arranged a support 98 for a lamp 99 having a reflector 100, the lamp being supplied with current by means of a suitable cable 101 running from the distributing box (Fig. 2).

Preferably, the thermostat 95 is set to provide a substantially constant temperature depending upon the material to be dispensed, but for use in dispensing popped corn, of the order of 135° to 140° F. and the blower is driven at such a rate as to produce a slightly superatmospheric pressure within the cabinet so that there is always an outward flow of air through the open top of the dispensing drawer.

Air from the heater is delivered through the conduit 93 into the space within the base between the bottom 2 and the perforate plates 58, 59 and 60, all such space except that occupied by the dispensing drawer and the above described apparatus in the semi-cylindrical space within the

wall 3 constituting a main plenum chamber P from which the air flows up through the perforations in plates 58, 59 and 60 and up through flues 16 and is distributed through the contents of the storage chamber. Simultaneously the air flows at superatmospheric pressure from the main plenum chamber directly through the inner end of the dispensing drawer into the chamber 57 beneath the dispensing chamber D, the chamber 57 constituting an auxiliary plenum chamber from which the air flows up through the perforations in the false bottom 54 into the dispensing chamber D and is distributed throughout the contents thereof and thence through the open top of the dispensing drawer. With the thermostat responsive to the air in the air conduit as illustrated and set for 140° F. the temperature in the cabinet and the dispensing chamber is maintained in the range of from about 125° F. to 140° F.

In use, the material to be dispensed is delivered into the cabinet through the top door 25 which, when open, provides an opening through which the material, for example popped corn, may be emptied. This material piles up on the perforated floor plates 58, 59 and 60 and in the freely visible storage space within the panels 10 and 11. When the material is to be dispensed, the drawer is pulled forwardly to the open position shown in Fig. 3 and the side members 66 are swung outwardly so as to provide sides for the upper side portions of the drawer.

The material from the cabinet flows down through the opening 64 onto the false bottom 54 of the dispensing chamber from whence it may be scooped up by the operator for delivery to purchasers. Throughout the operation of the apparatus warmed air is delivered by the blower 80 and the heater 92 into the main plenum chamber P thence upwardly through the perforate floor plates 58, 59 and 60 and through the flue 16 into the storage chamber and through the piled up contents thereby exposing the contents to a constant gentle flow of heated air. The heated air escapes by flowing downwardly through the contents of the storage chamber through the aperture 64 into the dispensing chamber and thence forwardly and upwardly through the upper portion of the contents of the dispensing chamber to the atmosphere through the open top of the drawer. Simultaneously warmed air at superatmospheric pressure is delivered from the main plenum chamber P forwardly directly into the auxiliary plenum chamber even to its extreme forward end, being assisted in this respect by the forward tapered shape of the chamber, thence flowing upwardly through the perforate false bottom 54 and into the dispensing chamber and thence upwardly through the entire contents thereof to the atmosphere through the open top of the dispensing drawer. Hot air thus passes through every portion of the material in the dispensing chamber and maintains it hot and crisp, and since no air can get at the contents of the cabinet or dispensing chamber except the hot and dry air delivered by the heating device and blower, the contents of the cabinet and dispensing chamber are protected from atmospheric moisture and it is found that the initial freshness and crispness of the material may be maintained for long periods, even for several weeks.

While ordinarily the heating of the air is sufficient to dry it enough for the purpose, it is contemplated that if desired the air from the blower, either before or after passing through the heater, may be caused to flow through moisture remov-

ing means of any suitable and customary type, thereby to remove moisture from the air before it is admitted to the dispensing cabinet. However, as already noted, satisfactory results may be obtained under most atmospheric conditions by merely heating the air before admitting it to the storage portions of the cabinet.

The transparent front door, in addition to the transparent end panels 10 and 11, provide a clear view of the interior of the cabinet so that its contents are readily visible to the passerby. The odor of the material, for example popped corn, is forced outwardly by the air which escapes through the top of the dispensing drawer and this is an inducement to purchasers.

If it be desired to stop the dispensing operation temporarily, the members 66 may be folded back and the drawer closed, thus bringing the forward wall 42 of the drawer into such a position as completely to close the space beneath the front door and thus to exclude air from the interior of the cabinet.

While one desirable embodiment of the invention has been illustrated by way of example, it is to be understood that the invention is not necessarily limited to this precise embodiment, but is inclusive of any and all modifications falling within the scope of the appended claims.

I claim:

1. A preserving and dispensing cabinet comprising a storage chamber having a perforate floor, a main plenum chamber beneath said floor, and an open-topped dispensing drawer slideable in and out of the cabinet beneath the floor of the storage chamber, said floor being provided with a freely open aperture whereby material flows by gravity from the storage chamber to the dispensing drawer, said dispensing drawer normally being withdrawn from the cabinet to permit ready access to the contents and to permit escape of air therethrough, and means operative to supply heated air at superatmospheric pressure to the main plenum chamber, the dispensing drawer having a false bottom above the bottom of the drawer, the false bottom having transverse perforations at the forward portion at least, the side walls, bottom and false bottom of the drawer forming an auxiliary plenum chamber with its inner open end in communication with said main plenum chamber, whereby a constant flow of heated air is maintained from the main plenum chamber into the auxiliary plenum chamber, thence upwardly into the part of the dispensing drawer above the perforate bottom, and thence through the contents of the drawer to the atmosphere.

2. A preserving and dispensing cabinet comprising a storage chamber having a perforate floor, a main plenum chamber beneath said floor, and an open-topped dispensing drawer slideable in and out of the cabinet beneath the floor of the storage chamber, said floor being provided with a freely open aperture whereby material flows by gravity from the storage chamber to the dispensing drawer, said dispensing drawer normally being withdrawn from the cabinet to permit ready access to the contents and to permit escape of air therethrough, and means operative to supply heated air at superatmospheric pressure to the main plenum chamber, the dispensing drawer having a forwardly and downwardly inclined false bottom above the bottom of the drawer, the false bottom having transverse perforations at the forward portion at least, the side walls, bottom and false bottom of the drawer

forming a forwardly tapered auxiliary plenum chamber with its inner open end in communication with said main plenum chamber, whereby a constant flow of heated air is maintained from the main plenum chamber into the auxiliary plenum chamber, thence upwardly into the part of the dispensing drawer above the perforate bottom, and thence through the contents of the drawer to the atmosphere.

- 5 3. A preserving and dispensing cabinet comprising a storage chamber having substantially imperforate back, side and top walls and a perforate floor whereby the part of said storage chamber which is located above said floor is substantially airtight, a main plenum chamber beneath said floor, an open-topped dispensing drawer slideable in and out of the cabinet beneath the floor of the storage chamber, said floor being provided with a freely open aperture whereby material flows by gravity from the storage chamber to the dispensing drawer, said dispensing drawer normally being withdrawn from the cabinet to permit ready access to the contents and to permit escape of air therethrough, and means operative to supply heated air at superatmospheric pressure to the main plenum chamber, whereby a constant flow of heated air is maintained from the main plenum chamber upwardly to the storage chamber through the perforate floor thence downwardly from the storage chamber through said aperture and into said dispensing drawer, thence outwardly and upwardly through the contents of the drawer to the atmosphere, the dispensing drawer having a false bottom above the bottom of the drawer, the false bottom having transverse perforations at the forward portions at least, the side walls, bottom and false bottom of the drawer forming an auxiliary plenum chamber with its inner open end in communication with said main plenum chamber, whereby a second constant flow of heated air is maintained from the main plenum chamber into said auxiliary plenum chamber, thence upwardly into the part of the dispensing drawer located above the perforate bottom, and thence through the contents of the drawer to the atmosphere.
- 10 4. A preserving and dispensing cabinet comprising a storage chamber having substantially imperforate back, side and top walls and a perforate floor whereby the part of said storage chamber which is located above said floor is substantially airtight, a main plenum chamber beneath said floor, an open-topped dispensing drawer slideable in and out of the cabinet beneath the floor of the storage chamber, said floor being provided with a freely open aperture whereby material flows by gravity from the storage chamber to the dispensing drawer, said dispensing drawer normally being withdrawn from the cabinet to permit ready access to the contents and to permit escape of air therethrough, and means operative to supply heated air at superatmospheric pressure to the main plenum chamber, whereby a constant flow of heated air is maintained from the main plenum chamber upwardly to the storage chamber through the perforate floor thence downwardly from the storage chamber through said aperture and into said dispensing drawer, thence outwardly and upwardly through the contents of the drawer to the atmosphere, the dispensing drawer having a forwardly and downwardly inclined false bottom above the bottom of the drawer, the false bottom having transverse perforations at the forward portion at least, the side walls, bottom and false bottom of the drawer
